UNITED STATES PATENT OFFICE.

MARY PHILLIPS, OF NEW YORK, N. Y., ASSIGNOR TO CHARLES C. CARPENTER,
OF SAME PLACE.

BOSOM-FORM.

SPECIFICATION forming part of Letters Patent No. 334,721, dated January 19, 1886.

Application filed September 19, 1885. Serial No. 177,528. (No model.)

To all whom it may concern:

Be it known that I, MARY PHILLIPS, a citizen of the United States, residing at New York city, in the county of New York and State of New York, have invented certain new and useful Improvements in Bosom-Pads; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to bosom-forms or breast-pads; and the novelty consists in the construction, arrangement, and adaptation of parts, as will be more fully hereinafter set forth, and specifically pointed out in the claims.

I have discovered a material and method of construction which produces an article closely resembling in elasticity, flexibility, and delicacy to the touch the natural bust. I employ a woven grass having grass both for the warp and woof, each blade of which has a peculiarly-glazed surface. Each blade is a tube, and at any period during the manufacture of the cloth this tube is flattened, producing in the finished cloth two flat thicknesses to each strand. The grass, when dried, is very tough, and the exterior glazing, which is a natural feature, allows each blade or strand to turn upon its neighbors with very little friction. Upon this latter feature and upon the additional features that each strand is of two thicknesses—the inner one of which is shortened or compressed endwise by the act of forming the cloth into a concave, and that the edges only are cemented, whereby the body of the pad is left free to move each strand upon the other, and the edges are more securely held than is possible by stitching—I rely for the peculiar advantages which accrue to my device. The grass mentioned is indigenous to China and Japan, and the woven cloth which I am now using in carrying out my invention comes to this country as wrappers for straw braid, tea-boxes, &c. I compress a section of the cloth between molds to obtain the desired form or convexity and secure the cut ends of the strands close to the mold by cement, the object being to hold the end firmly in place,

and thus insure permanently the form which was given by the mold. These forms, by a proper lining diaphragm and covering secured together in pairs, constitute a very useful, ornamental, and durable device for this purpose.

The invention is illustrated in the accompanying drawings, which form a part of this specification, and in which—

Figure 1 is a plan view of my improved pads partly broken away to show internal construction. Fig. 2 is an edge view, partly in section and partly in elevation. Fig. 3 is a plan of the fabric. Fig. 4 is a sectional view showing the manner of shaping and forming the fabric.

Referring to the drawings, A designates the woven-grass cloth, each blade or strand of which is a flattened tube, as seen at a. In molds D and D', I press sections of this cloth, as seen in Fig. 4, and then sever the cloth close to the mold. Before this section of the cloth is released from the mold I secure the ends of the strands a against independent movement by cement b. It will be understood that the action of the molds serves to shorten or compress the sides of the strands which are on the concave side, and to apply a tension to those sides which are on the convex portion. As the ends of the blades are held firmly against movement, it follows that the material will present a soft, very delicate, yet elastic and flexible surface. I find that it is exceedingly durable. Each form is cut with a lip, b', and they are properly bound and covered by a lacing or loose covering, C. The ordinary loose lining or diaphragm, G, and lacing-cords D' complete the structure. When the ends of the strands a are held, and the desired form has been given, pressure upon any point is accommodated over the entire area of the fabric A by the freedom with which the glazed strands move upon each other, and when the pressure is released the spring inherent in the fabric-strands readily and quickly forces the form back into normal position. Varied and continuous pressures will not break the strands. The fabric is exceedingly soft to the touch, the material is tough and durable, and will not break.

I am aware that woven straw or matting has

been before used, the same being secured in concavo-convex form to quilted pads by stitching. In such construction, however, some of the strands are left loose at the edges, and they 5 become useless.

In my device I form the fabric into concavo-convex forms by molds and thoroughly cement the edges, so as to hold each strand to its place, and maintain the form after it leaves 10 the molds. Being cemented only at the edges, the body of the pad is left free to move each strand upon the next. This provides the soft flexibility desired, and insures that each strand 15 will resume a normal position when pressure is removed.

What I claim as new is—

1. In breast-pads, a concavo-convex form composed of woven blades of grass having glazed surfaces, the edges of the form being

treated with cement to hold the strands in 20 place at those points and to maintain the shape of the form, and the strands having free movement upon and against each other at points other than along said edge, as and for the purpose set forth.

2. The breast-pad described, consisting of 25 the concavo-convex form or body, formed of woven grass and cemented at the edges only, as set forth, the cover, diaphragm, and lacing, all combined and arranged to serve as specified.

In testimony whereof I affix my signature in presence of two witnesses.

MARY PHILLIPS.
